Arthur R. Bentsen, Liverpool, N.Y., assignor to General Electric Company, a corporation of New York

Application March 4, 1958, Serial No. 49,892

Term of patent 14 years

(Cl. D26—13)

FIG. 1.

FIG. 2.

FIG. 3.

Figure 1 is a side elevational view of a feed-through switch embodying the new design, the opposite side being substantially a mirror image thereof;

Figure 2 is a top plan view of the switch of Figure 1; and

Figure 3 is a right end elevational view of the switch of Figure 1, the opposite end being substantially a mirror image thereof.

The broken line fragmentary showing of connecting wires are for illustrative purposes only.

I claim:

The ornamental design for a feed-through switch, substantially as shown and described.
